POWDER DISPENSER FOR BRUSHES

Manuel A. Jardines, S, Mayari, Cuba

Application October 8, 1948, Serial No. 53,575

4 Claims. (Cl. 222—510)

1

This invention relates to an improved fountain brush for tonsorial purposes and also relates to novel improvements in fountain brushes of the type adapted for use in scrubbing, cleaning or the like.

A primary object of this invention is to provide a brush, having a reservoir or compartment above the bristles, adapted to retain a supply of powder or the like material, means being provided to control the dispensing of the powder to the bristles.

This invention consists of other novel combination of elements including a hollow body defining a reservoir; a brush plate detachably secured to the body in a closure position on the reservoir, and slidably disposed valve means in said reservoir responsive to exterior manual pressure for controlling the dispensing of the powder in the reservoir through and to the tufts.

These and ancillary objects, which will become more fully apparent upon a perusal of the following description, are attained by this invention, a preferred embodiment of which is set forth in the following drawings, wherein:

Figure 1 is a top plan view of this invention;

Figure 2 is a bottom plan view of this invention;

Figure 3 is a bottom plan view, with the brush plate and contiguous nuts removed;

Figure 4 is an end elevational view of this invention;

Figure 5 is a longitudinal vertical sectional view taken substantially on the plane of line 5—5 of Figure 1;

Figure 6 is a transverse sectional view taken substantially on the plane of line 6—6 of Figure 5 looking in the direction of the arrows;

Figure 7 is a sectional view taken on line 7—7 of Figure 5 and looking in the direction of the arrows;

Figure 8 is an enlarged elevational view of one of the tufts, depicting the brush plate in sections and illustrating in section the means provided for frictionally retaining the tufts to the brush plate.

In carrying out this invention, there is provided a body section 10 of substantially egg-shape, which consists of a top 12 and an elliptical side wall 14. A handle 16 extends outwardly from the body section. A flange 18 is formed adjacent the lower end of the side wall 14 on the interior thereof and is provided with a plurality of spaced openings 20, as seen in Figure 3.

A brush plate 22 configured substantially as the body section 10 is formed with a plurality of

2

openings 24 adapted for registry with the openings 20. Suitable securing means, such as set screws 26 are received in the registered openings for detachably securing the brush plate to the hollow body section, so that the same functions as a bottom section for the body. The brush plate is provided with a series of depending bosses 28, as seen in Figure 8, within which are frictionally held the bristles and tufts 30, medially joined by a transverse securing member such as a piece of wire or the like.

The hollow body serves as a reservoir 32, within which is retained a quantity of powder or similar material, the same being disposed in the reservoir through an exteriorly threaded opening 34, which is provided with a detachable internally threaded cap member 36.

The brush plate 22 is provided with a series of openings 38, arranged in U-shaped fashion, as seen in Figure 7, whereby the powder or similar material may gravitate through and onto the tufts or bristles. In this respect, valve control means, generally designated by the reference character 40 is provided to control the quantity of material dispensed through the discharge openings 38 in the brush plate.

The manner of control means 40 comprises a slidably disposed valve plate 42, which is slidably mounted on the upper or inner surface of the brush plate 22 and is provided with a series of spaced discharge openings 44, which are selectively registerable with the discharge openings 38 in the brush plate. The valve plate 42 is longitudinally moved on the upper surface of the brush plate 22 by a longitudinally extending actuating bar 43, which is guided on the undersurface of the top of the brush head by a pair of parallel guide bars 46 and 48 depending from the top 12 of the body section, adjacent the filling openings 34. The operating bar is secured to the valve plate by vertical bars 50 and 52 and the rear portion of the bar terminates in a lateral extension 54 which protrudes exteriorly through an opening 56, adjacent the juncture of the body section and the handle 16. A finger manipulating member or slide button 58 is received on the lateral extension 54 and slidably disposed on the exterior surface of the handle and top 12 of the body section. The slide button 58 is provided with a pair of extending feet 60 and 62 which slidably engage on the outer surfaces of the top and handle section respectively. The alignment of the discharge openings 44 of the valve plate with the discharge openings 38 of the brush plate and movement of the valve plate relative to

an open and closed position is controlled by a stop plate 62, against which the forward foot 60 of the slide button abuts upon alignment of the discharge openings in an opened position. In a similar fashion, a finger or pin 64 extends rearwardly from the operating bar 44 and is adapted to engage against a transverse member 66 positioned in the handle section, when the valve plate is moved relative to a closed position.

In operation, the brush is held and manipulated by the extending handle 16 and the thumb of an operator is disposed on the slide button 58 so that the quantity of material dispensed from the reservoir to the tufts can be easily controlled as the brush is being manipulated. For example, when the brush is in use by a barber in applying powder to the neck of a customer, the tufts are moved across the neck of the customer and the powder is dispensed from the reservoir through the exertion of pressure by the barber upon the slide button 58, which can be controlled by his thumb.

It is to be particularly noted that the brush plate and the valve means are detachably secured to the body section, which is formed integral with the handle section. Thus, all of the parts or elements of the device may be easily and conveniently removed for cleaning and sterilization.

Of course, to fill reservoir, it is only necessary to move the cap 36, so that the brush is at all times convenient for use. In embodying this invention for use in other types of brushes, such as scrubbing brushes or the like, wherein steel or relatively rigid tufts are used, the same may be carried out without any material change in the structural formation and elements, as noted above. The utility of this invention would still be inherent therein and the same would be adaptable for many uses.

Having described the invention, what is claimed as new is:

1. In a brush comprising a casing defining a material reservoir and having a top wall, depending side walls and an apertured bottom wall, valve plate means for controlling the discharge of the material through the apertures in the bottom wall including an apertured plate slidably superimposed on the bottom wall, an elongated operating arm mounted for sliding movement on the interior of the top wall, guide means for said arm, connecting means between said arm and plate and means extending from the arm and slidably disposed through the top wall for actuating said arm.

2. In a brush comprising a casing defining a material reservoir and having a top wall, depending side walls and an apertured bottom wall, valve means for controlling the discharge of the material through the apertures in the bot-

tom wall including an apertured plate slidably superimposed on the bottom wall, an elongated operating arm mounted for sliding movement on the interior of the top wall, guide means for said arm, connecting means between said arm and plate and a lateral extension on the rear end of the arm positioned through the top wall, and a button member encompassing the outer end of the extension and slidably disposed on the top wall.

3. In a brush comprising a casing defining a material reservoir and having a top wall, depending side walls and an apertured bottom wall, valve means for controlling the discharge of the material through the apertures in the bottom wall including an apertured plate slidably superimposed on the bottom wall, an elongated operating arm mounted for sliding movement on the interior of the top wall, guide means for said arm, connecting means between said arm and plate and means extending from the arm and slidably disposed through the top wall for actuating said arm, said guide means including a pair of longitudinally disposed members extending downwardly from the top wall and laterally spaced apart to receive the arm positioned therebetween.

4. In a brush comprising a casing defining a material reservoir and having a top wall, depending side walls and an apertured bottom wall, valve means for controlling the discharge of the material through the apertures in the bottom wall including an apertured plate slidably superimposed on the bottom wall, an elongated operating arm mounted for sliding movement on the interior of the top wall, guide means for said arm, connecting means between said arm and plate and means extending from the arm and slidably disposed through the top wall for actuating said arm, and stop means in said casing for limiting reciprocatory movement of the arm and aligning the apertures in the plate with the apertures in the bottom wall.
